UNITED STATES PATENT OFFICE.

HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROL SYSTEM.

1,421,242.

Specification of Letters Patent. Patented June 27, 1922.

Application filed January 8, 1919. Serial No. 270,147.

To all whom it may concern:

Be it known that I, HENRY D. JAMES, a citizen of the United States, and a resident of Edgewood Park, in the county of Allegheny and State of Pennsylvania, have invented a new and useful Improvement in Control Systems, of which the following is a specification.

My invention relates to motor-control systems and particularly to systems of the type forming the subject-matter of my co-pending application Serial No. 236,937, filed May 27, 1918, in which the accelerating resistor is controlled by contactors, the closing 15 of which is effected by relays which are in turn controlled by a coil in parallel circuit with the resistor.

The object of my invention is to provide such a system, the controlling coil of which 20 shall be in series relation to the resistor.

According to the present invention, the relays are designed to be successively actuated, in accordance with circuit conditions, upon successive portions of the coil becoming short-circuited by the preceding relays 25 to close.

Figure 1 is a diagrammatic view of a system arranged according to my invention, and Figs. 2 and 3 are, respectively, a 30 side and an end elevation of a relay device such as is preferably employed in connection with my motor.

Referring to Fig. 1, a motor, the armature of which is shown at 1 and the shunt 35 field-magnet winding at 2, is connected between line conductors 3 and 4, with an accelerating resistor 6 in series with the armature 1. The resistor is adapted to be short-circuited upon the closing of contactors 10, 40 11 and 12, which respectively control resistor portions 13, 14 and 15. The contactors 10, 11 and 12 are closed by energizing coils 19, 20 and 21, the circuits of which are controlled by relays 25, 26 and 27, which 45 are respectively controlled by a coil 22, divided into three portions, 23a, 23b and 23c, the points of connection of which are respectively connected to the contactor 10 by a conductor 17 and to the contactors 11 and 50 12, in parallel, by a conductor 18. A switch 7 is adapted to connect the motor, the resistor and the coil 22 to the line conductors 3 and 4.

The preferred relay mechanism is shown 55 in Figs. 2 and 3. An insulating panel 29 carries two brackets 30 and 31 supporting

the coil 22 which, when energized by current flowing through it, creates a magnetic field for attracting an armature 32 and any desired number of additional armatures 33. 60 A compression spring 36 is adjustably mounted upon a non-magnetizable rod 37 slidably mounted in projections 38 and 39 which are rigidly connected to, or are integral parts of, the bracket 31. The projections 38 and 39 serve also as pole pieces for the armatures 32 and 33, respectively. A bar 40 is rigidly connected to the rod 37, and normally engages the armatures 33. The spring 36 thus normally maintains the 70 armatures 33 in open position, with the members 41, which are carried by these armatures, in contact with the pole piece 39. The members 41 are preferably of non-magnetizable material to prevent freezing. 75

The armature 32 is provided with brackets 42, which are pivotally mounted upon the bracket 30, and is normally retained in the broken-line position, (Fig. 2), by a weak spring 43. The bracket 30 supports a non-magnetizable U-shaped member 44, between the arms of which are pivotally mounted the armatures 33, which carry, respectively, the movable contact members 45, 46 and 47 of the relays 25, 26 and 27, shown in Figs. 2 85 and 3 as closed. The stationary contact members 48, 49 and 50 of the relays 25, 26 and 27 are mounted upon the insulating panel 29. Springs 51 are attached to longitudinally adjustable members 52 and to the 90 other ends of the members 41. The pole piece 39 is provided with longitudinally adjustable members 53 to regulate air gaps 70 between these members and the corresponding armatures. By means of this adjustment, or by means of the members 52, the action of the magnetic flux produced by the coil 22 may be so regulated that the armatures 33 will be operated in proper sequence. 95

The operation is as follows: Upon the closing of the switch 7, the motor circuit is established from the line conductor 3, through the armature 1 and the resistor 6 and the field-magnet winding 2 in parallel, 105 the coil 22 and the switch 7, to the line conductor 4. The coil 22 is accordingly energized to actuate the armature 32 into the full-line position of Fig. 2, whereupon the armatures 33 are released from the restraining influence of the spring 36. Initially, 110 the current is too high to permit the springs

51 to close their armatures, but as the motor accelerates, the current value decreases. When the current falls to a predetermined value, the relay 25 will be closed by its 5 spring 51 to cause the closing of a circuit extending from the line conductor 3, by way of a conductor 28, through the relay 25, the coils 19 and 22 and the switch 7 to the line conductor 4. The contactor 10 will, thereupon, 10 be closed to short-circuit the resistor portion 13 and also the coil portion 23a. The armature circuit may now be traced from the line conductor 3, through the armature 1, the resistor portions 15 and 14, the 15 contactor 10, the conductor 17, the coil portions 23b and 23c and the switch 7 to the line conductor 4. As the motor accelerates further and the current, consequently, drops to a lower value, the relay 26 will be closed to 20 cause the energization of the coil 20 and the consequent short-circuiting of the resistor portion 14 and the coil portion 23b. The relay 27 will ultimately close when the current traversing the motor falls to a sufficiently 25 low value, whereupon the contactor 12 will be closed to short-circuit the resistor portion 15. The motor will now be connected directly across the line, and the coil portion 23c will be maintained in the motor circuit 30 to maintain the armature 32 in the actuated position illustrated in Fig. 2.

I have shown my invention as embodying a switch of particular construction. As the coil 22 is in series with the motor, and as 35 the successive current peaks, following the successive short-circuiting operations, are nearly of equal value, I have provided for controlling the relays by currents of substantially different value by tapping the coil 40 22, as shown.

It will be understood, however, that the operation of my system is by no means dependent upon the use of the particular relay mechanism illustrated in Figs. 2 and 3 and 45 that my invention is not limited to the use of a series coil in the particular manner which is herein illustrated and described. I desire, therefore, that my invention be construed as broadly as is indicated in the 50 appended claims.

I claim as my invention:

1. The combination with an electric motor having a resistor associated therewith, a plurality of electro-magnetic switches for controlling said resistor, and a relay for controlling said switches and having an energizing coil in series with said motor, said coil being operable to maintain said relay open upon the closing of the circuit of 55 said motor so long as the current traversing said circuit exceeds a predetermined value, and means comprising the first of said switches to close for shunting a portion of said energizing coil of said relay.

60 2. The combination with an electric motor

having a resistor associated therewith, a switch for controlling said resistor and means for normally maintaining said switch open, of an energizing coil for rendering said means ineffective to maintain said switch 70 open under predetermined conditions, and a circuit controlled by said switch whereby a portion of said coil is de-energized upon the closing of said switch.

3. The combination with an electric motor 75 having a resistor associated therewith, a relay comprising a plurality of pairs of contact members for controlling said resistor and an energizing coil for said relay, said pairs of contact members being operable at 80 different degrees of force exerted by said coil, of means for shunting a portion of said coil upon the operation of the first pair of contact members to close.

4. The combination with an electric motor 85 having a resistor associated therewith and means comprising a pair of normally open switches for controlling said resistor, said switches being biased to closed positions, of 90 a coil in series with said resistor for maintaining said switches open when the current traversing said coil is above predetermined values, and means for shunting a portion of said coil upon the closing of one of said switches.

5. The combination with an electric motor 95 having a resistor associated therewith, a pair of switches for controlling said resistor and means for normally maintaining said 100 switches open, of an energizing coil for rendering said maintaining means effective or ineffective in accordance with predetermined conditions, said switches being controlled by different current values of said coil, and means for short-circuiting a portion of said coil upon the closing of one of said switches and for maintaining a portion of said coil in circuit after the closing of said other switch.

6. The combination with an electric motor 110 having an armature, a resistor in series therewith, a plurality of switches for short-circuiting said resistor, a relay for each switch and means for normally maintaining 115 said relays open, of a coil in series with said resistor for rendering said maintaining means effective or ineffective to maintain said relays open according as the current traversing said coil is above or below predetermined values, and means for short-circuiting a portion of said coil upon the closing of all the relays except the last to close 120 and for maintaining a portion of said coil in the motor circuit after the closing of the last contactor to close.

In testimony whereof, I have hereunto 125 subscribed my name this 21st day of Dec., 1918.

HENRY D. JAMES.
